SCREWLESS HOLDER

Filed Sept. 26, 1932

FIG. 1.

FIG. 2.

INVENTOR

James J. Flynn
BY
Harry Leo Carlson
ATTORNEY

UNITED STATES PATENT OFFICE

JAMES J. FLYNN, OF CAMDEN, NEW JERSEY, ASSIGNOR TO FARIES MANUFACTURING COMPANY, OF DECATUR, ILLINOIS, A CORPORATION OF ILLINOIS

SCREWLESS HOLDER

Application filed September 26, 1932. Serial No. 634,899.

My invention relates to that class of holders designed to support one of the enclosing glass globes which are so much employed at present in illumination.

5 The principal object of my invention is to provide a holder which will automatically hold the globe in the correct position.

A further object is to provide means to release the holder without the use of tools when it is desired to gain access to the interior of the globe for cleaning or relamping.

10 My means of accomplishing the foregoing objects may be more readily understood by having reference to the accompanying drawing which is hereunto annexed and is a part 15 hereof, in which

Fig. 1 is a side view of my holder, the exterior collar being shown in section; and

Fig. 2 is a top or plan view of the holder.

20 Similar reference numerals refer to similar parts throughout the entire description.

As shown in the drawing, the holder is formed of an outer or exterior shell or collar 1 which is provided with a central opening 2. 25 This collar is flared outwardly and terminates in a vertical cylinder portion 3. The inner shell consists of a cylinder member 4 closed at the top except for an opening 5 adapted to receive the loop or stem of the 30 support which is not shown as obviously it is no part of my invention. The cylinder member 4 is provided with a plurality of lugs 6 which may conveniently be punched out of its walls, as shown they are three in number.

35 The diameter of the cylinder member 4 is such that it will slidably fit the opening 2 in the exterior collar 1. The edges of the opening 2 are provided with notches which are adapted to register with the lugs 6. Arms

40 7, 8 and 9 are secured to the cylinder member 4 by spot welding or in any other convenient or desired manner. These arms 7, 8 and 9 extend radially from the cylinder member 4 in a downward and outward direction. Each

45 one of the arms 7, 8 and 9 has a tongue 10 which extends upwardly from the arm adjacent its outer end. As illustrated these tongues 10 are stamped out of the metal of which the arms are formed although it will 50 be obvious they may, if desired, be formed

separately and secured to the arms in some convenient manner. The operation of my holder is as follows:

The outer shell 1 is rotated until the notches are in register with the lugs 6 when it is raised upwardly until it is clear of the cylinder member 4. The globe 11, only a fragmentary portion of which is shown, as obviously it is no part of my invention since it may be of any desired shape or configuration, 60 is tipped until the arms 7 and 8 can be inserted when by shifting the position of the globe 11 the arm 9 may be passed into the interior of the globe 11, the neck 12 of which will abut the tongues 10. The outer collar 1 is then 65 placed over the cylinder member 4 in such position that the notches formed in the edge of its central opening will register with the lugs 6 and the lower edge of the vertical cylinder portion 3 contacts the outer wall of the 70 globe 11. The outer collar 1 is then rotated until the notches are out of register with the lugs 6 and in such position the lugs 6 will operate to hold the outer collar 1 against vertical movement in an upwardly direction when 75 it will be apparent that the glass globe 11 will be held securely and correctly in position. It will also be seen from the foregoing description that it can be removed without the use of any tools or screws.

Having described my invention what I regard as new and desire to secure by Letters Patent is:

1. A device of the character described comprising an outer collar having a central opening therein, there being a plurality of notches in the edge of said opening, a cylinder member which fits said opening, a plurality of lugs thereon adapted to register with said notches, a plurality of arms secured to said cylinder member which extend radially therefrom and in an outward and downward direction, a vertical tongue on each arm adjacent its lower end, said tongue adapted to engage the inner side of a globe to be supported.

2. A device of the character described comprising an outer collar having a central opening therein, there being a plurality of notches in the edge of said opening, a cylinder member which fits said opening, a plurality of

lugs thereon adapted to register with said notches, a plurality of arms secured to said cylinder member which extend radially therefrom the in an outward and downward direction, a vertical tongue stamped from each arm adjacent its lower end, said tongue adapted to engage the inner side of a globe to be supported.

3. A device of the character described comprising an outer collar having a central opening therein, there being a plurality of notches in the edge of said opening, a cylinder member which fits said opening, a plurality of lugs thereon adapted to register with said notches, a plurality of arms secured to said cylinder member which extend radially therefrom and in an outward and downward direction, a vertical tongue stamped from each arm adjacent its lower end, said tongue adapted to engage the inner side of a globe to be supported, said collar flaring outwardly and downwardly and terminating in a vertical cylindrical portion.

4. A device of the character described comprising an outer collar having a central opening therein, there being a plurality of notches in the edge of said opening, a cylinder member which fits said opening, means on said cylinder members to hold said collar against upwardly movement when in position, said means being adapted to register with said notches, a plurality of arms secured to said cylinder member which extend radially therefrom and in an outward and downward direction, a vertical tongue on each arm adjacent its lower end, said tongue adapted to engage the inner side of a globe to be supported.

40.

JAMES J. FLYNN.
